UNITED STATES PATENT OFFICE.

LEO G. MULLEN, OF CRAFTON, PENNSYLVANIA.

DESIGN FOR A PRISM-LENS.

45,123.

Specification for Design.

Patented Jan. 6, 1914.

Application filed October 23, 1913. Serial No. 796,973. Term of patent 7 years.

To all whom it may concern:

Be it known that I, LEO G. MULLEN, a citizen of the United States, residing at the city of Crafton, in the county of Allegheny and State of Pennsylvania, have invented a new, original, and ornamental Design for a Prism-Lens, of which the following is a specification, reference being had to the accompanying drawing, forming part thereof.

Figure 1 is a bottom plan view, and Fig. 2 is a view partly in side elevation and partly

in central section of a prism lens, showing my new design.

I claim:

The ornamental design for a prism lens, as shown.

In testimony whereof I affix my signature in presence of two witnesses.

LEO G. MULLEN.
